UNITED STATES PATENT OFFICE

FRANK B. COONEY, OF SANDUSKY, OHIO, ASSIGNOR TO THE AMERICAN CRAYON COMPANY, OF SANDUSKY, OHIO, A CORPORATION OF OHIO

NONDRIP SIPHON AND AGITATOR

Application filed December 14, 1929. Serial No. 414,074.

This invention relates to a non-drip siphon and agitator; its object being the provision of an improved apparatus of this character which will be simple in construction and highly efficient in operation, and more particularly one which will insure cleanliness in operation.

An object of the invention is the provision in association with an air pressure tube of an air pressure control vent tube which is normally open to relieve air pressure in the siphon bottle and thereby prevent discharge of the liquid either by accident or through curiosity, and which is so arranged that it can be easily and conveniently closed by the forefinger or thumb when operating the air compressor bulb, the arrangement in this regard being such that when the vent tube is closed the liquid can be freely transferred through the delivery tube, and when the closing finger or thumb is removed the liquid under transfer and within the delivery tube will be instantly siphoned back so as to prevent any drip from the discharge end of the delivery tube.

An other object of the invention is the provision of an apparatus having a delivery tube which extends to a point closely adjacent the bottom of the siphon bottle to avoid the necessity of inclining the siphon bottle when liquid is to be transferred, and at the same time to provide means whereby the delivery tube may be employed as an agitator especially useful for liquids which show a sediment and require agitation in order to secure homogeneous distribution and uniform strength before transference.

The apparatus of the present invention is especially useful in schools, offices, and other places where there is frequent necessity for replenishing the supply of small ink bottles and stands, although the apparatus is not confined to such particular use, as it may be used for the transfer of any kind of liquid and particularly where it is desired to effect the transfer without drip or waste and with cleanliness in operation.

Other objects and aspects of the invention will appear hereinafter.

The invention consists in the improved

non-drip siphon and agitator and in the construction and relative arrangement or arrangements of parts, as will be hereinafter more fully described and subsequently incorporated in the subjoined claim.

The invention will be best understood by referring to the accompanying drawing, which forms a material part of this specification, and in which—

Figure 1 represents an elevational view 60 showing the apparatus applied to a siphon bottle;

Fig. 2 represents a vertical fragmentary sectional view of the apparatus, detached from the siphon bottle and shown on a larger 65 scale; and

Fig. 3 represents a plan and section on the line 3—3 of Fig. 2.

The preferred form of construction, as illustrated in the accompanying drawing, 70 comprises a stopper 10 made preferably of flexible rubber and of a size and shape to have relatively tight fit in the neck of the siphon bottle with which it is intended to be used. In Fig. 1 the stopper 10 is illustrated as fitted in the neck of the siphon bottle 11.

According to my invention, the stopper 10 carries three separate tubes, 12, 13 and 14; each made preferably of hard rubber and extending well above the top surface of the 80 stopper. The tube 12, which for convenience of reference may be referred to as the pressure tube, is made with a laterally curved top end 15. Detachably associated with the curved end 15 is an air compressor or bulb 85 16, the mode of attachment as herein illustrated consisting in providing the compressor with a hollow stem or nipple 17 adapted to be inserted in the open top end 15 and to have frictional engagement with the interior 90 thereof. The tube 13 comprises a finger engaging vent tube, its upper portion 18 being bent laterally in the same direction as the upper end portion 15 and being in close proximity thereto, so that its open end 18' may be 95 instantly closed and opened by a finger of the hand engaging with and operating the air compressor 16. The third part or tube 14 comprises the liquid delivery tube, the upper portion 19 of this tube being curved laterally 100

and sufficiently to constitute a discharging nozzle for the liquid. It will be observed that the nozzle portion 19 is curved laterally in a direction away from the upper portions of the other tubes 12 and 13, so that the liquid will be discharged at the side of the siphon bottle opposite to the projection of the laterally curved upper portions 15 and 18 where space is required for ready and convenient manual operation.

In the present exemplification, each of the tubes 12, 13 and 14 extends downwardly through the stopper, the tubes 12 and 13 terminating just below the lower surface of the stopper and above the level 20 for the liquid within the siphon bottle. The delivery tube 14 extends well below the stopper, its length being such that its open lower end 21 will come closely adjacent to the bottom 22 of the siphon bottle. In order to suit bottles differing in height, the delivery tube 14 is made so as to be adjustable in the direction of its length. To this end the lower part 21 of this tube is made separate from the upper part thereof and these two parts are connected by a coupling tube 23. The mode of connecting these parts consists preferably in providing them with cooperating screw-threads so that the coupling tube 23 may be screw-threaded upon the upper part, while the lower part 21 is screw-threaded into the coupling tube as shown. By this arrangement, the length of the delivery tube below the stopper may be varied by turning the lower part 21, and further by turning the coupling tube 23 if it be necessary to do so in order to effect the desired lengthwise adjustment to compensate for the length of the siphon bottle and bring the lower open end 40 of the part 21 in close adjacency to the bottom 22 of the siphon bottle.

In the operation of the apparatus, when it is desired to discharge liquid from the siphon bottle, the air compressor 16 is compressed and simultaneous with this action the forefinger or thumb is placed firmly over the open top end 18' of the vent tube. By these conjoint operations, air is introduced under pressure into the top of the bottle upon the surface of the liquid therein contained, and since this compressed air cannot escape through the vent tube, liquid from adjacent the bottom of the bottle is forced upwardly through the delivery tube and discharged 55 through the nozzle end 19. In this way, pressure upon the air compressor with the vent tube closed by the finger will result in a steady discharge of the liquid without tilting or inclining the siphon bottle. By removing the finger from the open end 18' of the vent tube, air pressure upon the liquid is instantly relieved so that the flow from the nozzle will instantly cease, and with the further result that the liquid under discharge within the delivery tube and nozzle portion 19 thereof will

be instantly siphoned back without drip from the down-turned end of the nozzle portion 19.

As has been previously pointed out, the air compressor or bulb 16 is detachably engaged with the upper end 15 of the pressure tube 12. Now the interior delivery end of the nozzle portion 19 is of substantially the same size as the interior of the end 15, so that the nipple 17 can be fitted into the end of the nozzle portion 19. The object of this provision is to enable the air compressor or bulb 16 to be detached from the pressure tube and attached to the delivery tube whenever it is desired to agitate the liquid contained within the siphon bottle. Thus, by transferring the air compressor or bulb 16 to the nozzle end of the delivery tube the siphon apparatus becomes an agitator, so that by making pressure upon the bulb any sediment which has settled in the bottom of the siphon bottle will be stirred up and re-intermixed in order to provide a homogeneous and uniform liquid before discharging it from the bottle.

Since the vent tube is normally open at its top end, there can be no accidental discharge of the liquid from the siphon bottle; for liquid can be discharged only when the finger is firmly placed upon the open top end of the vent tube simultaneously with the operation of the air compressor or bulb. Mischievous trifling, therefore, with the air compressor by small children will not result in a discharge of the liquid. By the apparatus of my invention, ink can be siphoned into small bottles or stands without danger of overfilling and with thorough cleanliness, since there is no drip from the nozzle portion. By making all of the parts from hard rubber no corrosion results where iron gall inks are used; and moreover, no chemical change can take place in the ink so as to render it unfit for use, as is frequently the case where the ink is permitted to contact with soft rubber.

It will be apparent from the foregoing that I have produced a novel and useful construction of non-drip siphon and agitator and one which embodies the features of advantage enumerated in the statement of the invention and the above description, and while I have, in the present instance, shown and described a preferred embodiment thereof as reduced to practice, it is to be understood that the apparatus is susceptible of modification in various particulars without departing from the spirit or scope of my invention or sacrificing any of its advantages.

I claim:

A liquid delivering device for bottles comprising a stopper adapted to be fitted into the bottle neck, a delivery tube for the liquid extending through said stopper having a laterally and downwardly curved outer discharge end, a pair of additional tubes extending through said stopper and having their outer

ends laterally curved, a hand operated air compressor having means for interchangeable connection with said curved end of one of the latter tubes and the outer end of the delivery tube to force air under pressure into the bottle, and the other of said last named tubes constituting an air vent having an unobstructed bore, and the outer open end thereof being positioned above and substantially in the same vertical plane with the air inlet tube for the convenient application of the thumb to said open end of the vent tube while the liquid is being delivered by the operation of the air compressor through said delivery tube.

In testimony that I claim the foregoing as my invention, I have signed my name hereto.

FRANK B. COONEY.
